SANDING BLOCK

James F. McAdams, Worcester, Mass., assignor to
Parker Wire Goods Company, Worcester, Mass.,
a corporation of Massachusetts

Application August 8, 1940, Serial No. 351,857

6 Claims. (Cl. 51—187)

This invention relates to sanding blocks, that is, devices for holding extended for use a portion of sheet-like abrasive material such as sandpaper, emery cloth or the like. The name "sanding block" is due to the fact that the prototype of such a device is in fact a solid block of wood to which a workman tacks a piece of sandpaper. The present device, on the contrary, is in the nature of a permanent appliance or tool formed of sheet metal and in the preferred form herein illustrated comprises essentially but two unitary sheet metal pieces whereby there is most effectively attained the object of the invention to provide a simple and inexpensive construction, nevertheless durable and convenient and efficient to use. In one aspect of the present invention it may be considered as an improvement on the device shown in my application Serial No. 319,376, filed Feb. 17, 1940, wherein certain generic features are claimed.

My invention will be well understood by reference to the following description of the illustrative embodiment thereof shown by way of example in the accompanying drawing, wherein:

Fig. 1 is a side elevation;

Fig. 2 is a longitudinal section with parts in a different position;

Fig. 3 is a section on the line 3—3 of Fig. 1; and

Fig. 4 is a fragmentary plan view with parts in section on the line 4—4 of Fig. 2.

Referring to the device as illustrated in preferred form in the drawing, as there shown it comprises a bottom member of generally channel form comprising a web 6 having downwardly extending longitudinal flanges 8 which give the same a desirable stiffness and also define a groove to receive the sponge rubber pad 10 which in use underlies the abrasive sheet 12. The flanges 8 may extend along and support the rearwardly rising end flanges 14 which terminate in rolled portions 16. From the web 6 are struck teeth 18 adapted to imbed themselves in the pad 10 and prevent the same from shifting, and there also may be struck up from the base a part 20 forming a partition defining a chamber between the same and the left-hand flange in Fig. 2 and which will hereinafter be referred to.

The cooperating member which is in the nature of a cover is also of a general channel form and comprises a web 22 from which extend longitudinally depending flanges 24 which may have finger-receiving grooves 26 along their sides. The depth of these flanges is such that when the two members are assembled, as in Figs. 1 and 3,

they will extend substantially to the web 6 of the base plate and they are of a length to span the distance between the end flanges 14, thus providing between the members a box-like enclosure, as best seen in Fig. 3. Between the side flanges are end flanges 28 and 30, unattached to the side flanges and thus resiliently yieldable. Adjacent the web 22 these flanges 28 and 30 are concaved as shown to fit the rolled portions 16. The proportion of the parts is such that when the flanges are forced between these rolled portions they will be placed under stress providing a snap-acting engagement of the two members, which herein, because of the stiffening of the end flanges 14 by the extensions of the longitudinal flanges 8 is primarily due to the resiliency of the end flanges 28 and 30.

The upper or cover member is herein hinged at one end and for this purpose tongues 32 having inwardly bent ends, as shown in Fig. 4, may be cut from the side flanges 24. Prior to the assembly of the parts these tongues may be bent outwardly, as shown in dotted lines at the bottom of Fig. 4, and when the rolled element 16 at the left-hand end in Fig. 2 is introduced between the same they may be bent inwardly to the full line position so that the inturned ends enter into the rolled portion, thus providing a pivotal connection.

The flange 28 may terminate as shown shortly below the concavity thereof which fits the roll 16. The end flange 30 seen at the right in Fig. 2, on the contrary, is preferably extended downwardly to provide a relatively long and flexible extension 33 having an inturned terminal serving as a guide similar to the extension on the strike plate of a door lock, which, as the parts are closed, engages the inner surface of the rolled portion 16 beneath the same to be pressed thereby toward the left in the figure until the rolled portion snaps into the concavity which is to receive the same. Herein the upper member carries the male portions of the snap-engaging parts and the flanges 24 are extended, as perhaps best seen in Fig. 2, past the end flanges 28 and 30 and laterally overlie the mating pairs of end flanges of the two members.

In use a strip of abrasive material 12 may be threaded through the joint of the hinge at the left of Fig. 2 over the pad 10 and the end tucked inwardly over the right-hand flange 14 to be caught and clamped by the flange 30 when the parts are closed while the proximal end is clamped by the flange 28. Herein I have shown the strip 12 as a portion dispensed from a roll

34 which may be received in the compartment formed at the left-hand of the partition 20, viewing Fig. 2. The end of this strip may be threaded once for all through the joint of the hinge at the left, and when the parts are opened the worn part of the strip may be torn off and a new length drawn out through the joint until its end will reach the right-hand end of the device in some such position as is shown in Fig. 2. One of the flanges 24 may be provided with a sight opening 36 (Fig. 1) opening to the compartment referred to so that one may see how much of the roll has been used up.

The flange 30 may be provided with an opening 38 in such a position that in the closed position of the parts it lies just above the top of the cooperating flange 14. This opening provides for the insertion of a prying instrument to separate the parts. Herein I have shown a suitable prying instrument permanently mounted as an accessory of the device as a whole, and for this purpose I may provide a lever having the relatively offset, generally parallel portions 40 and 42 connected by a web 44 which is received in a narrow slot 46 formed in the top 22 of the cover member. The part 42 extends outwardly through the aperture 38 and terminally overlies the upper rolled end 16 of the flange 14 while the part 40 lies flat on the top 22 which may have an opening 48 cut therethrough to admit the finger to engage the lower surface of the part 40, permitting it to be rocked clockwise in the figure so that the end 42 will press downwardly on the part 16 to separate the parts. To provide for the assembly of the prying lever slits may be cut from the slot 44 to provide a tongue 50 which initially may take the dotted line position shown in Fig. 2 providing a relatively large opening permitting the cranked prying lever to be assembled with the end 42 extended through the opening 48. The tongue may then be closed back into the plane of the top 22 and the lever will be irremovably suspended in the slot 46. It will be noted that in rocking the lever clockwise, viewing Fig. 2, the fulcrum is provided by the right-hand margin of slot 46 so that there is no tendency to displace the tongue 50 after it has been bent back into the plane of the top 22.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. A sanding block comprising a bottom member having end flanges upwardly turned and terminally rolled and a cover member having side flanges of an area substantially corresponding to the space between the flanges and web of the bottom member and having end flanges between said side flanges, which end flanges are concaved to fit the rolled portions, the side flanges having instruck tongues entering one of the rolled terminals to provide a pivot, the end flange of the lid member at the opposite end having a yielding extension below the concaved portion providing a guide for engaging the two members together with a snap action.

2. A sanding block comprising a bottom member having upwardly turned end flanges and a cover member having side flanges to extend between said end flanges and of a depth to extend to the web of the bottom member to define a box-like enclosure and also having end flanges, the end flanges of the members being cooperatively profiled to provide for a snap engagement thereof to retain the two members together and providing for the clamping of the ends of an abrasive strip therebetween, one end flange having an opening at a location corresponding substantially to the edge of the cooperating flange when the members are engaged, said opening providing access for a pry to separate the members.

3. A sanding block comprising essentially two sheet metal pieces, one comprising a base having upwardly turned end flanges and side flanges extending along the base and the end flanges and the other comprising a top having yieldable end flanges to telescope into snap-acting engagement with the end flanges first mentioned, said other member having side flanges independent of said end flanges of a depth to reach substantially to said base and terminally extended to overlie the engaged pairs of end flanges.

4. In a structure of the class described comprising two sheet metal members telescoped to form a box-like structure with overlapping, mutually gripping walls corresponding to at least a part of the periphery thereof, one wall having an aperture adjacent the edge of the overlapping wall, a relatively perpendicular face of the structure having a slot, and an opener device having generally parallel offset ends connected by a web which is received in said slot, one end extending through the aperture to oppose said edge of the overlapping wall and the other end normally overlying said face.

5. A sanding block comprising a bottom member having end flanges upwardly turned and terminally rolled and a cover member having side flanges of an area substantially corresponding to the space between the flanges and web of the bottom member, means for engaging said side flanges with one of said end flanges to provide a hinge joint presenting a passage through which a strip may be threaded over the said one end flange, the other end of the cover member having a depending portion to oppose the other end flange, the said portion and other end flange being cooperatively profiled to provide for a snap engagement thereof to retain the two members together and providing for the clamping of the ends of an abrasive strip therebetween.

6. A sanding block comprising a bottom member having upwardly turned end flanges and a cover member having side flanges to extend between said end flanges and of a depth to extend to the web of the bottom member to define a box-like enclosure and also having end flanges, the end flanges of the members being cooperatively profiled to provide for a snap engagement thereof to retain the two members together and providing for the clamping of the ends of an abrasive strip therebetween, the several end flanges being received in the closed position of the parts entirely between said side flanges of the cover.

JAMES F. McADAMS.
